PACKING CO., OF SAN FRANCISCO, CALIFORNIA, A CORPORATION OF CALIFORNIA.

CAN-OPENER.

1,145,343.

Specification of Letters Patent.

Patented July 6, 1915.

Application filed April 3, 1915. Serial No. 19,018.

To all whom it may concern:

Be it known that I, CHARLES H. WORKMAN, a citizen of the United States, residing in the city and county of San Francisco and State of California, have invented new and useful Improvements in Can-Openers, of which the following is a specification.

This invention relates to a can opener.

One of the objects of the present invention is to provide a simple, substantial, easily operated can opener which is provided with a rotary cutter, and which is also provided with means for supporting and gripping the can while the cutting operation is taking place.

Further objects will hereinafter appear.

The invention consists of the parts and the construction and combination of parts as hereinafter more fully described and claimed, having reference to the accompanying drawings, in which—

Figure 1 is a plan view of the can opener. Fig. 2 is a cross section of same on line 2—2, Fig. 1. Fig. 3 is a detail view showing 25 interlocking of the fixed and movable jaws. Fig. 4 is a detail section on line 4—4 of Fig. 1. Fig. 5 is a detail, vertical section on line 5—5 of Fig. 2.

A indicates a cutting head which is adapted to be turned or rotated by means of a handle 2. The handle is pivotally mounted, as at 3, in lugs 4 formed on top of the head and is adapted to be tilted into the full line position shown in Fig. 2 and automatically 35 returned to the normal position indicated by dotted lines in said figure by a spring 5. The upward movement of the lever is limited by a lug 6, while the downward or depressing movement is limited by a lug 7.

Slidably mounted in the head, in slots 8 formed between the arm supporting lugs, is a vertically positioned cutting knife 9. The upper end of this knife is provided with a slot 10 through which a projection on lug 5' extends. The lower end of the knife is suitably pointed or shaped, as indicated at 11, to produce a cutting edge. The knife is operated by means of the handle, or, in other words, raised or lowered by same through 45 the connection provided by the lug, and may in this manner be depressed to puncture the top of the can indicated at 12.

The head as a whole is supported between two gripping jaws 13 and 14, one of which 55 is stationary while the other is pivotally

mounted with relation thereto, as indicated at 15. Formed integrally with the stationary jaw is a screw clamp, such as indicated at 16, by which the can opener as a whole may be secured to the edge of a table or the like. Suitably secured on the lower end of the clamp is a platform 17 upon which the can to be opened is supported.

Pivottally mounted in the outer end of the movable jaw is a lever 18, on the inner end 65 of which is formed a hook or catch 19 which is adapted to be swung into engagement with a lug 20 formed on the stationary jaw. The cutting head is adapted to be rotated when the movable jaw is swung into closed position and when the locking lever is thrown into position where its inner hooked end engages with the co-operating lug; the head being turned by means of the handle 2, previously described.

In operation, when it is desired to open a can, it is only necessary to release the movable jaw and swing it into the open or dotted line position indicated in Fig. 1. The can to be opened is then placed on the supporting platform and moved into position below the rotary cutting head. The movable jaw is then swung back and locked, as previously described. This operation does not only secure the rotary cutting head in position but also clamps the can against movement; the stationary and movable jaws being sufficiently deep to embrace the upper part of the can. Handle 2 is then depressed, as shown in Fig. 2, causing the knife to enter 80 the can. It is then rotated one revolution, causing the knife to form a circular cut which severs the head from the can. The handle is then released and is automatically returned to the dotted line position shown 85 in Fig. 2 by means of the spring 5; the same movement causing the knife to be retracted out of engagement with the can. The movable jaw is now unlocked and swung back about its pivot to the dotted line position 90 shown in Fig. 1 and the can removed.

The upper face of each jaw is provided with a semi-circular groove 21 into which a pin 22, secured in the cutting head, is adapted to register. Said grooves form a complete circle when the jaws are closed. The pin in this instance merely serves as a means to retain the cutting head in the fixed jaw while the movable jaw is thrown into the open position. The jaws are also provided 100

105 to 110

with a second groove, such as indicated at 26, and the cutting head proper is provided with an outwardly extending flange which fits said groove. The head is thus completely locked from removal while the jaws are closed but is free to rotate.

Formed at each end of the stationary jaw is an outwardly projecting shoulder 23, and formed at each end of the swinging jaw is 10 a recess 24. These recesses register with the shoulders 23 when the jaws are closed and this forms a means for supporting the movable jaw while the head is being rotated. This is of considerable importance, as the 15 whole strain would otherwise have to be supported by the pivot about which the movable jaw swings.

The cutting knife provided in the present instance is also of considerable importance, 20 as it has two cutting edges, thus permitting the head to be revolved in either direction. The center portion of the knife, furthermore, has a tendency to turn in the cut edge against the side of the can, thus smoothing 25 it off and destroying the cut edge which is generally left on the can by ordinary can openers.

The materials and finish of the several 30 parts of the device may be such as the experience and judgment of the manufacturer may dictate.

I wish it understood that various changes in form, proportions and minor details of construction may be resorted to within the 35 scope of the appended claims, and that I do not wish to limit myself to the specific design and construction here shown.

Having thus described my invention, what I claim and desire to secure by Letters Patent is—

1. A can opener comprising, in combination, a rotary head, means for supporting a can below said head, a vertically positioned knife reciprocally mounted in the head, 45 means for depressing said knife so that it will enter the can head, and means for rotating the head.

2. A can opener comprising, in combination, a rotary head, a pair of jaws in which 50 said head is mounted, one of said jaws being pivotally mounted with relation to the other, means for locking said jaws to inclose and grip the can to be opened, a knife mounted in the head, means for depressing said knife 55 to enter the can top, and means for rotating the head.

3. A can opener comprising, in combination, a rotary head, a pair of jaws in which 60 said head is mounted, one of said jaws being pivotally mounted with relation to the other, means for locking said jaws to inclose and grip the can to be opened, a knife mounted in the head, means for depressing said knife to enter the can top, 65 means for rotating the head, and means for

automatically raising the knife out of engagement with the can.

4. A can opener comprising, in combination, a rotary head, a pair of jaws in which 70 said head is mounted, one of said jaws being pivotally mounted with relation to the other, means for locking said jaws to inclose and grip the can to be opened, an arm pivotally mounted on the head, said head having a vertically positioned slot formed therein, a knife slidably mounted in said slot, means for depressing the arm, and a connection formed between the arm and knife to depress the knife in unison with the arm. 75

5. A can opener comprising, in combination, a rotary head, a pair of jaws in which 80 said head is mounted, one of said jaws being pivotally mounted with relation to the other, means for locking said jaws to inclose and grip the can to be opened, an arm pivotally mounted on the head, said head having a vertically positioned slot formed therein, a knife slidably mounted in said slot, means for depressing the arm, a connection 85 formed between the arm and knife to depress the knife in unison with the arm, and means for automatically raising the arm and knife. 90

6. A can opener comprising, in combination, a rotary head, a pair of jaws in 95 which said head is mounted, one of said jaws being pivotally mounted with relation to the other, means for locking said jaws to inclose and grip the can to be opened, an arm pivotally mounted on the head, said head having a vertically positioned slot formed therein, a knife slidably mounted in said slot, means for depressing the arm, a connection formed between the arm and knife to depress the knife in unison with the arm, 100 and means for automatically raising the arm and knife, said means comprising a spring interposed between the arm and head. 105

7. A can opener comprising, in combination, a rotary head, a pair of jaws in 110 which said head is mounted, one of said jaws being pivotally mounted with relation to the other, means for locking said jaws to inclose and grip the can to be opened, an arm pivotally mounted on the head, said head having a vertically positioned slot formed therein, a knife slidably mounted in 115 said slot, means for depressing the arm, a connection formed between the arm and knife to depress the knife in unison with the arm, a spring interposed between the arm and head to automatically raise the arm and knife, and means for limiting the pivotal movement of the arm in either direction. 120

8. A can opener comprising, in combination, a rotary head, a pair of jaws in which 125 said head is mounted, one of said jaws being pivotally mounted with relation to the other, a locking lever pivotally mounted with relation to the other, a locking lever 130

pivottally mounted on the movable jaw having a hook-shaped member formed on its inner end, a lug on the stationary jaw with which the hook-shaped member is adapted to interlock, said jaws being adapted to inclose the head and grip the can to be opened, an arm pivotally mounted on the head, said head having a vertically positioned slot formed therein, a knife slidably mounted in said slot, means for depressing the arm a connection formed between the arm and knife to depress the knife in unison with the

arms, a spring interposed between the arm and head to automatically raise the arm and knife, and means for limiting the pivotal movement of the arm in either direction.

In testimony whereof I have hereunto set my hand in the presence of two subscribing witnesses.

CHARLES H. WORKMAN.
